CLAIM

The ornamental design for a display screen with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image of a display screen with animated graphical user interface; and,

FIG. 2 is a front view of a second image thereof.

The broken line showing of a display screen with animated graphical user interface is for the purpose of illustrating portions of the article and forms no part of the claimed design.

The appearance of the transitional image sequentially transitions between the images shown in FIG. 1-2. The process or period that one image transitions to another image forms no part of the claimed design.
